(57) CLAIM

I claim the ornamental design for a jacket cover for cellular phone, as shown.

DESCRIPTION

FIG. 1 is a perspective view of a jacket cover for a cellular phone.

FIG. 2 is a front view of the jacket cover for a cellular phone

FIG. 3 is a back view of the jacket cover for a cellular phone

FIG. 4 is a side view of the jacket cover for a cellular phone

cellular phone

FIG. 6 is a bottom view of the jacket cover for a cellular
phone

FIG. 7 is a top view of the jacket cover for a cellular phone

FIG. 8 is the perspective view of FIG. 1 with a cell phone therein, shown in broken lines; and,

FIG. 9 is the side view of FIG. 4 with a cell phone therein,

The broken line showings of the cell phone in FIGS. 8 and 9 are for illustrative purposes only and form no part of the claimed design.
